CLAIM

The ornamental design for a dishwasher rack and sprayer, as shown and described.

DESCRIPTION

FIG. 1 is a top perspective view of a dishwasher rack with sprayer, showing our new design;

FIG. 2 is a bottom perspective view thereof;

FIG. 3 is a front view thereof;

FIG. 4 is a right side view thereof;

FIG. 5 is a left side view thereof;

FIG. 6 is rear view thereof;

FIG. 7 is a top view thereof; and,

FIG. 8 is a bottom view thereof.

The portions of the dishwasher rack with sprayer shown in broken lines form no part of the claimed design.

1 Claim, 8 Drawing Sheets
